UNITED STATES PATENT OFFICE.

WILHELM GYSIN, OF GENF, SWITZERLAND.

PENCIL POINTER.

Application filed August 26, 1924, Serial No. 734,318, and in Germany August 30, 1923.

My invention relates to an improved pencil-pointer, which is combined with a crank for turning the cutter in the manner of the known pointing-machines affixed to a table or the like, but which offers the particular advantage to be of a more simple kind and of such small size that it may be conveniently carried in a waist-coat-pocket, like the known pointers, which latter, on being used, are applied and turned by one hand, while the other hand holds the pencil in a stationary position. Such pointers of the usual kind are subjected to the deficiency, that the point of the pencil will frequently come to break when the fingers, which turn the little pointing-device, but slightly swerve from the straight line which, normally, rigidly holds the pencil. To prevent such breaking of the point, I have combined to the said pointing apparatus a movable guiding device. By the aid of such movable guide all the securities are provided, which are offered by the known pointing machines which to be used are secured to a table for preventing the deviation of the cutter from the straight line.

In the accompanying drawings I have illustrated my invention. Fig. 1 shows the pointing-device in side-elevation, mounted on top of a pencil to be pointed. Fig. 2 shows, how the working is performed by turning the crank. Fig. 3 is a longitudinal section of the device taken in the plane of the pivoted crank.

35 *a* is the small pointing-device of the usual type, having a conical bore to fit the top of

the pencil, a shoulder *b* is formed to said device and the usual pointing-knife is fixed to said shoulder by means of a screw *c*. At the opposite side of said device *a*, another shoulder *e* has been provided within a passing groove *d* of which a crank *f* is pivoted to turn on the pivot *g*. The said crank *f* has an extension *i* beyond the pivot *g*, the purpose of which extension is, to permit the said crank to be slightly raised, as indicated by dotted lines, for allowing the fork *h* of the extension *i* to find a resistance on the pencil. The pencil will accommodate itself to the actual pressure applied on turning the said crank. The said fork *h* for clasping the pencil corresponding the actual pressure applied, will keep the point of the lead in permanent, straight line with the revolving pointing-device *a*, and, thereby, prevent any 55 tendency of breaking or hurting the point of the lead.

I claim as my invention:

An improved pencil-pointer, comprising a cutting-device of a known construction, a removable cutting-knife secured within the bore of said device, a groove cut into the length of said device, an arm pivoted to turn within said groove, an extension formed to the rear of said arm, a fork secured to the rear of said extension for clasping the shaft of the pencil, and a crank secured to the front of said arm for turning the said cutting-device, substantially as set forth.

In testimony whereof I have affixed my 70 signature.

WILHELM GYSIN.
